UNITED STATES PATENT OFFICE.

THOMAS H. GIBBON, OF ALBANY, NEW YORK, ASSIGNOR OF ONE-HALF TO
DUDLEY FARLIN, OF SAME PLACE.

RAILWAY-RAIL JOINT.

SPECIFICATION forming part of Letters Patent No. 288,704, dated November 20, 1883.

Application filed July 26, 1883. (No model.)

To all whom it may concern:

Be it known that I, THOMAS H. GIBBON, of the city and county of Albany, in the State of New York, have invented certain new and 5 useful Improvements in Railway-Rail Joints, of which the following is a specification.

My invention relates to improvements in that class of rail-joints in which the conjoining ends of the lengths of rails have their heads 10 cut away to receive a connecting-piece provided with a head which conforms to the shape of the rail-head.

The objects of my improvement are to provide an effective and reliable joint of simple 15 construction, and to afford the means for interlocking the connecting device with the cross-ties, so as to prevent the spreading of the rails, and thereby avoid a most frequent source of serious accidents. These objects I 20 attain by means of the construction illustrated in the accompanying drawings, which form part of this specification, and in which—

Figure 1 is a side elevation of my improved joint; Fig. 2, a plan view of same; Fig. 3, a 25 transverse section at the line x x of Fig. 1; Fig. 4, a side elevation of connecting-piece, and Fig. 5 a side elevation of one end of a length of rail.

As illustrated in the drawings, A indicates 30 the rails; B, the connecting-piece; C, the fastening-plate, and D the cross-tie.

The rails A may be made of any of the forms of T-rail that are commonly used, or of any other form that is suitable for containing my 35 form of joint. At each end of every length of said rail the head a should be cut away, as at a' , Fig. 5, to a distance that is equal to one-half of the length of the head of the connecting-piece, and to such a depth as will leave 40 the upper edge of the web a^2 uniform in thickness with the remainder of said web. The said cutting away may be effected in such manner as to form a right angle, as shown in Fig. 5; or, when preferred, the corner of the angle 45 may be filleted by leaving a slight curve, as indicated by the dotted lines in Fig. 5.

The connecting-piece B is preferably cast of steel, and is provided with a head, b , that conforms to the shape of the head a of the rails.

Integral with the head b are two side plates, 50 b' —by which a groove, c , is formed to fit upon the web a^2 of the rails—and the said side plates project outwardly to form the flanges b^2 , which fit snugly over the bottom flanges, a^3 , of the rails, and are then projected downward to 55 form the vertical flanges b^3 , which pass down at each side of the bottom flanges, a^3 , of the rails, as shown in Fig. 3. The flanges b^2 and b^3 extend endwise beyond the head b and side plates, b' , in the proportion of about three to 60 one, and by this means the weakening of the rails by cutting away of the heads a is reduced to a minimum, and the support afforded to the bottom flanges of the rails is maintained at a maximum. Sufficient space is left between the shoulders d of the flanges b^2 to permit the head of the rails to pass through freely. The vertical flanges b^3 are provided with longitudinal mortises or openings b^4 , for receiving 65 the fastening-plate.

The fastening-plate C is adapted to pass 70 through the openings b^4 of the connecting-piece. The said fastening-plate is provided at one end with hooked projections c' —which prevent the said plate from passing too far 75 into the openings b^4 —and at both ends it has holes c^2 , for containing spikes or other means for securing said plate in place.

The cross-tie D is one of the series commonly used on the road-bed for securing the 80 rails to. The said cross-tie is adapted to receive my improved connecting-piece B by having suitable crosswise grooves cut therein to receive the vertical flanges b^3 , as shown in Figs. 1 and 3, which grooves, by binding the connecting-piece B sidewise, prevent the rails 85 from spreading at the joints.

As illustrated in the drawings, my connecting-piece B is shown as when the rail-joint comes directly over a cross-tie, D, in which 90 case the grooves in said cross-tie serve to retain the connecting-piece in place sidewise, and additional security is given to the joint by means of spikes c^3 , which are driven through the holes c^2 into the cross-tie D, and it is in 95 such places and under like conditions that I prefer to use my improved joint; but it may be used where the joints of the rails come in-

termediately between two cross-ties, and under such conditions the holes c^2 may be utilized for receiving bolts or other stop devices for securing the fastening-piece C in place.

5 I am aware that the heads of railway-rails have heretofore been cut away for the purpose of receiving a connecting device of different construction from mine; therefore I do not broadly claim the cutting away of the rail-heads; but

I claim as my invention—

In a rail-joint, the rails A, having the heads of their conjoining ends cut away, as at a' , as herein described, and a connecting-piece, B, 15 consisting of a head, b , that conforms to the heads a of the conjoining rails, side plates, b' ,

having a uniform length with the head b , flanges b^2 , adapted to fit over the bottom rail-flanges, a^3 , and vertical flanges b^3 , provided with openings b^4 , the said flanges b^2 and b^3 being made of greater length than the side plates, b' , as herein set forth, in combination with the fastening-piece C and cross-tie D, the latter being provided with transverse grooves for receiving the vertical flanges b^3 and retaining 25 the connecting-piece B in place, all substantially as herein specified.

THOS. H. GIBBON.
